CLAIM

The ornamental design for a cabinet door locking handle, as shown and described.

DESCRIPTION

FIG. 1 is a perspective view of a cabinet door locking handle showing my new design;
FIG. 2 is a top view thereof;
FIG. 3 is a left side view thereof;
FIG. 4 is a right side view thereof;
FIG. 5 is a front view thereof;
FIG. 6 is a rear view thereof; and,
FIG. 7 is a bottom view thereof.

(Continued)

The broken lines shown represent unclaimed subject matter and form no part of the claimed design.
